ADHESIVE APPLYING MEANS FOR COATING
RECEPTACLE CLOSURE CAPSJohn C. Johnson, East Hempstead, N.Y., and
Walter H. Johnson, Newmanktown, Pa.

Application June 3, 1949, Serial No. 96,842

5 Claims. (Cl. 118—262)

1

This invention relates to adhesive applying means adapted to coat receptacle closure caps with a film of adhesive prior to assembling sealing pads in said closure caps.

It is an object of the invention to provide adhesive applying means of this character consisting of an adhesive transfer wheel rotatably mounted on a receptacle to collect adhesive contained therein and a series of daubers adjustably mounted in a peripheral edge portion of a wheel rotatably mounted in the plane of rotation of the adhesive transfer wheel to successively position the daubers into contact with the adhesive on the transfer wheel and subsequently into the closure caps traveling below and in vertical alignment with the wheels.

It is another object of the invention to adjustably mount the adhesive transfer wheel on the receptacle whereby said wheel is adjustably positioned relative to the adhesive in the receptacle and the daubers to vary the amount of adhesive applied to the daubers and subsequently to the closure caps.

It is a further object of the invention to provide a scraper adjustably mounted on the receptacle and readily adjustable relative to the peripheral and side portions of the adhesive transfer wheel to remove excess adhesive and foreign substances from said wheel.

Another object of the invention is to removably and adjustably mount the receptacle on closure cap assembling machines to facilitate cleaning and varying the height of the receptacle.

Other objects and advantages of the invention will be set forth in the detailed description of the invention.

In the drawings accompanying and forming a part of this application, Figure 1 is a side elevational view of the adhesive applying means forming the embodiment of this invention.

Figure 2 is a plan view of the means shown in Figure 1.

Figure 3 is a fragmentary sectional view of a dauber and its carrying wheel to show the adjustable mounting of the dauber.

The embodiment of the invention is particularly adapted to be used in the apparatus shown in our co-pending application Serial No. 787,238, filed November 20, 1947, now Patent 2,522,577, issued September 19, 1950, and the closure cap supporting rails of said apparatus are shown in a general way at 4.

A receptacle 5 for adhesive is supported from the table of said closure cap assembling apparatus to extend over the closure cap supporting rails

by a standard 6 mounted on said table indicated in a general way at 7 in Figure 1 and having a transverse portion 8 secured at the upper end and arranged at the opposite end sections with slots 9 extending downwardly from the upper edge of said transverse portion. The receptacle is provided with projections in the form of screws 10 secured at one end portion in a side wall of the receptacle and the opposite end adapted to be adjustably engaged in the slots 9 and retained in adjusted position in said slots by wing nuts 11 engaged on the sections of said end portions of the screws projecting from the outer face of the transverse member.

15 The side wall of the receptacle 5 opposite the side wall arranged with the projections 10 is provided with a boss 12 for the pivotal mounting of an arm 13 having a pin 14 projecting from a face at one end portion therefor and pivotally secured in the boss 12 by a screw 15 secured in the pin 14 and abutting a washer 16 against the boss, as shown in Figure 2. The opposite end portion of the arm 13 extends at an obtuse angle therefrom as shown at 17. At the angle portion between the 20 opposite end portions of the arm, there is provided a bearing boss 18 for the rotatable mounting of a shaft 19 having the opposite end portions extending from the boss. One of said end portions of the shaft 19 supports an adhesive transfer wheel 20 secured to said end portion by screws 21 engaged partially in the wheel and the end of the shaft, as shown at 21 in Figures 1 and 2. The opposite end portion of the shaft 19 is of reduced diameter and supports a pulley 22 secured to said end portion by a set pin 23 as shown in Figure 2.

25 The adhesive transfer wheel 20 is adjusted about the pivot 12, 14 relative to the adhesive in the receptacle 5 and daubers to be hereinafter described. This is accomplished by an adjusting member connected to the end portion 17 and comprising a tubular member internally screw threaded and having an annular enlarged end portion or shoulder 23 and a manipulating portion 24 at the opposite end. The intermediate portion of the tubular member is rotatable in a vertical extension 25 at a corner portion of the receptacle 5. A screw threaded shank 26 is adjustably engaged with the screw threads of the tubular member 23, 24 and is provided at one 30 end with an elongated vertical slot 27 for the adjustable engagement of a pin 28 secured in the arm end portion 17. The rotation of the tubular member by grasping the manipulating portion 24 will impart longitudinal movement to the shank 26 and pivotal movement to the arm 13.

The arm 13 is locked in adjusted position by a wing nut 29 engaged on the end portion of the shank 26 projecting from the manipulating portion 24 in abutting engagement with the manipulating portion.

Excessive adhesive and foreign substances on the transfer wheel 20 are removed by a scraper in the form of a plate 30 having slots 31 therein for the engagement of screws 32 screw threaded in an end wall of the receptacle 5 to adjustably mount the plate on said end wall for adjusting the plate toward and away from the transfer wheel. The end portion of the plate 30 engaging the transfer wheel is bifurcated to permit engagement of the peripheral and side portions of the wheel by said end portion, as shown at 33 in Figure 2. The opposite end portion of the scraper plate 30 is flanged upwardly, as at 34, for fixed connection to one end of an adjusting member in the form of a screw 35 adjustably mounted in a lug 36 secured to a shelf portion 37 extending as a lateral extension of the top edge of the end wall of the receptacle 5 to partially support the scraper plate 30, as shown in Figures 1 and 2. The opposite end portion of the adjusting screw 35 is extended from the lug 36 and is arranged with a manipulating knob 38 secured thereto. Upon loosening of the screws 32 rotation of the screw 35 through the knob 38 adjusts the scraper plate toward and away from the transfer wheel 20 and when the scraper plate is adjusted to a desired position, the locking nuts 32 are tightened.

The adhesive on the transfer wheel is transferred to a series of daubers rotating as a unit in the plane of rotation of the transfer wheel. Each dauber comprises an adhesive applicator or spreader 39 secured in a holder 40 having a shank 41 arranged with a tapered end 42. The shank 41 of each dauber is engaged in a corresponding opening 43 of a series of openings equidistantly spaced in the peripheral edge portion and extending radially of a wheel 44 keyed to an end portion of a shaft 45 rotatably mounted in a bearing standard 46 supported on the table 7. A pulley 47 is secured to the opposite end portion of the shaft 45 and operatively connected to the pulley 22 by a transmission belt 48. The shaft 45 is driven from the drive shaft of the closure cap assembling machine through a shaft 49 rotatably mounted in bearings 50 and 51 supported in vertical spaced alignment by the bearing standard 46. The shaft 49 is operatively connected at the lower end to and driven by the drive shaft of the assembling machine in a suitable manner not shown. The shaft 49 is operatively connected to the shaft 45 by a worm 52 secured to the upper end portion of the shaft 49 and meshing with a worm wheel 53 secured to the end of the shaft 45 projecting from the pulley 47, whereby the drive shaft of the assembling machine drives the adhesive transfer wheel 20 and the dauber carrying wheel 44. The daubers are adjustably mounted in the wheel 44 to have adjustment radially of said wheel by an adjusting screw 54 having a tapering end 55 and adjustably engaged in a screw threaded opening in the wheel 44 relative to the bottom of each opening 43 to engage the tapering end 55 with the tapering end 42 of the dauber shank 41 whereby adjustment of the adjusting screw 54 into the wheel will adjust the dauber radially outward from the wheel and adjustment of the adjusting screw outwardly from the wheel will permit the daubers to be adjusted into the wheel openings 43. The daubers are

retained in adjusted position by a set screw 56 screw threaded in the wheel relative to each opening 43 to abut the shank 41 of each dauber, as shown in Figure 3.

5 By the rotation of the wheels 20 and 44, freshly adhesive coated portions of the periphery of the wheel 20 will contact and apply a film of adhesive on the spreader 39 of successive daubers and said film of adhesive is transferred by said spreader to a closure cap C on the supporting rails 4 below and in vertical alignment with the shaft 45.

The adjustment of the adhesive transfer wheel 20 by the adjusting mechanism 23'-27 will vary the thickness of the film of adhesive applied by the wheel 20 to the dauber spreaders 39 and subsequently by the spreaders to the closure caps.

Having thus described our invention, we claim:

1. In adhesive applying means, an open top receptacle for adhesive, an adhesive transfer wheel rotatably supported by the receptacle with a peripheral portion of the wheel extending into the receptacle to collect adhesive thereon, a second wheel having a series of radially extending openings in the peripheral edge portion and rotatably mounted in spaced relation to the receptacle and in the plane of rotation of the adhesive transfer wheel, a series of daubers having an adhesive spreader at one end and a shank at the opposite end arranged with a tapering end for adjustable engagement in the openings in the second wheel with the adhesive spreader contacting and receiving adhesive from the adhesive transfer wheel during the rotation of both wheels, an adjusting screw having a tapering end and adjustably mounted in the second wheel relative to each opening to engage the tapering end thereof with the tapering end of the shank and adjust the dauber radially of said wheel, and a set screw adjustably mounted in the second wheel relative to each opening to engage an intermediate portion of the shank and secure the dauber in adjusted position in said wheel.

2. In adhesive applying means, an open top receptacle for adhesive, an arm pivotally mounted at one end on a side wall of the receptacle, an adhesive transfer wheel rotatably supported by an intermediate portion of the arm with a peripheral portion of the wheel extending into the receptacle to collect adhesive thereon, a tubular member internally screw threaded and rotatably supported on a corner portion of the receptacle, and a screw threaded shank adjustably engaged with the screw threads of the tubular member and adjustably connected at one end to the arm whereby rotation of the tubular member imparting longitudinal movement to the shank and adjusting the axis of rotation of the adhesive transfer wheel in an arc about the pivotal mounting of the arm.

3. Adhesive applying means as claimed in claim 2, wherein the screw threaded shank is adjustably engaged at an intermediate portion with the screw threads of the tubular member and has an elongated slot at one end, and a pin secured in the free end of the arm and engaged in said slot to adjustably connect the shank to the arm and transmit longitudinal adjustment of the shank to pivotal adjustment of the arm and vary the position of the adhesive transfer wheel relative to the adhesive in the receptacle.

4. Adhesive applying means as claimed in claim 2, wherein the screw threaded shank is adjustably engaged at an intermediate portion with the screw threads of the tubular member and has an

elongated slot at one end portion, a lock nut engaged on the opposite end portion of the shank extending from the tubular member to retain the shank in adjusted position in the tubular member, and a pin secured in the free end of the arm and engaged in said slot to adjustably connect the shank to the arm and transmit longitudinal adjustment of the shank to pivotal adjustment of the arm and vary the position of the adhesive transfer wheel relative to the adhesive in the receptacle.

5. In adhesive applying means as claimed in claim 2, a standard having a transverse portion at the upper end arranged with elongated slots extending downwardly from the upper edge of said portion, projections secured in and extending from the receptacle to engage in said slots and removably and adjustably support the receptacle on the standard, and members removably engaged on the end portions of the project-
